Primary Examiner — Amy C Wierenga*Assistant Examiner* — Kathryn Elizabeth Zieno(74) *Attorney, Agent, or Firm* — David M. Quinlan, P.C.(57) **CLAIM**

The ornamental design for a nozzle cartridge for steam trap, as shown and described.

DESCRIPTION

FIG. 1 is an isometric view of a nozzle cartridge for steam trap, showing our new design;

FIG. 2 is a front elevational view thereof;

FIG. 3 is a rear elevational view thereof;

FIG. 4 is right elevational view thereof;

FIG. 5 is a left elevational view thereof;

FIG. 6 is a top elevational view thereof; and,

FIG. 7 is a bottom elevational view thereof.

The broken lines shown in the drawings depict portions of the nozzle cartridge for steam trap that form no part of the claimed design.
